UNITED STATES PATENT OFFICE.

MALCOLM GIBSON, OF DAVISVILLE, ONTARIO, CANADA.

AUTOMATIC FIRE-ALARM.

1,031,707.

Specification of Letters Patent.

Patented July 9, 1912.

Application filed October 30, 1911. Serial No. 657,470.

To all whom it may concern:

Be it known that I, MALCOLM GIBSON, a subject of the King of Great Britain, resident of Davisville, county of York, Province of Ontario, in the Dominion of Canada, have invented certain new and useful Improvements in Automatic Fire-Alarms; and I do hereby declare that the following is a full, clear, and exact description of the 10 same.

The invention relates to improvements in automatic fire alarms, as described in the following specification and illustrated in the accompanying drawing that forms part 15 of the same.

The invention consists essentially in the novel construction and arrangement of parts, whereby an alarm is given on the rising of the temperature to a pre-determined point.

The objects of the invention are, to give warning of an undue increase of temperature, thus prematurely stopping fires and to devise an alarm which will ordinarily 25 operate through the rise of a thermometer but will not be rendered inoperative in the event of the thermometer being broken.

Figure 1 of the drawing represents a perspective view of my device shown partly 30 in section. Fig. 2 is a vertical sectional view showing the thermometer supporting means.

Referring to the drawing, 1 is a plate having the flanges 2 formed at the top and 35 bottom ends, said plate being adapted to be secured to the wall in a furnace room or any other place where it is desired to locate the alarm.

3 is a bracket adjustably secured to the 40 plate 1 adjacent to the bottom and having a pocket or recess 4 in the top thereof, said bracket projecting laterally from the front face of said plate.

5 is a thermometer having the bulb end 45 6 resting in the pocket 4 of the bracket.

7 is a spring tongue secured to the back of the plate 1 and extending through the slot 8 adjacent to the top of said plate, said tongue projecting forwardly and having a 50 pair of pin holes 9 therein.

10 is a bar having a suitable recess formed in its under side midway of its length adapted to receive the top end of the thermometer 5, said bar having the cylindrical portions 11 formed at its outer ends, 55 said cylindrical portions being open at the

bottom. The spring tongue 7 engages the pins projecting upwardly from the bar 10 thus holding it securely in position and holding the thermometer in place.

60

12 are bolts or binding posts suitably insulated from the plate 1 and extending therethrough, being electrically connected from their inner ends back of said plate to a suitable alarm bell 13, a suitable battery 65 being interposed in the electric circuit.

14 are wires connected to the outwardly projecting ends of the binding posts 12 and having their terminal ends inserted into and held in suitable orifices 15 in the side 70 of the thermometer 5, the ends of said wires extending into the mercury tube so that the column of mercury, on rising through an increase in temperature, will, at a certain pre-determined height, form an electrical 75 connection between the terminal ends of the said wires, thereby closing the electric circuit and causing the alarm bell to operate.

16 are rods secured to the binding screws 12 and extending upwardly therefrom into 80 the cylinders 17 secured in the cylindrical end portions 11 of the cross bar 10. The rods 16 which are preferably of brass are supported from contact with the metal parts of the cross bar 10 by a filling 18 of shellac, 85 paraffin, or other fusible insulating cement.

In the use of this device, there is ordinarily no strain whatsoever upon the rods 16 or upon the cement holding them in their vertical position. An abnormal increase in 90 temperature causes the mercury column to rise to close the alarm signal circuit.

If the thermometer is broken by any means, the cross bar 10 is supported against the pressure of the spring tongue by the 95 fusible cement in the cylinders 17 and in the event of the temperature rising to an abnormal heat the cement is softened and the pressure of the spring tongue forces the bar 10 downwardly until it rests upon the end 100 of the rods 16. An electrical connection is thus established between the binding posts to close the alarm circuit.

It will be readily seen that a device such as described will operate very readily on 105 the rise of temperature through the electrical connection established by the mercury column but that in the event of failure of the mercury column through breakage, the device will still act to give warning.

110

What I claim as my invention is:—

1. In an automatic fire alarm, an electri-

cally operated signal, a pair of leads from the signal circuit having branched ends, a thermometer having its mercury column arranged to close the electrical circuit through 5 one pair of said branches at a pre-determined temperature, and means adapted to automatically close the electrical connection of the circuit through the other branches at a pre-determined temperature in the 10 event of the thermometer being broken.

2. In an automatic fire alarm, an electrically operated signal, a pair of leads from the signal circuit having branched ends, a thermometer having its mercury column arranged 15 to close the electrical circuit through one pair of said branches at a pre-determined temperature, an electrical conductor supported by said thermometer adjacent to the terminal ends of the other pair of 20 branched ends of said leads and adapted to be moved into contact therewith following the breaking of the thermometer, and an insulating fusible cement holding said electrical conductor out of contact with said secondary branch terminals. 25

3. In an automatic fire alarm, an electrically operated signal, a pair of leads from the signal circuit having branched ends, a thermometer having its mercury column arranged 30 to close the electrical circuit through one pair of said branches at a pre-determined temperature, a metallic cross bar supported by said thermometer and having tubular extensions therefrom, a pair of elec-

tric terminals forming the secondary 35 branches of said electric circuit extending into said tubular extensions, and a fusible insulating cement arranged within said tubular extensions and embracing said terminals, said cement being adapted to hold the 40 electrical conductor from electrical contact with said terminals to a slightly higher temperature than the temperature at which the electrical circuit to the former terminals would be closed by the mercury column. 45

4. In an automatic fire alarm, a supporting plate, a thermometer supported from said plate, an alarm circuit having a pair of electrical terminals inserted into said thermometer and adapted to be electrically 50 connected together on the rise of the mercury column, a pair of electric terminals arranged one to each side of said thermometer and electrically connected to the aforesaid terminals, a bar supported on the top of 55 said thermometer above said latter terminals and supported from said terminals by a fusible insulating cement, and a spring member secured to said supporting plate and bearing downwardly against said cross 60 bar.

Signed at the city of Toronto, county of York, Ontario, Canada, this 13th day of October 1911.

MALCOLM GIBSON.
